(57) **CLAIM**

The ornamental design for a deep socket for a recessed anchor hold down, as shown and described.

DESCRIPTION

FIG. 1 is a perspective view of the present invention.

FIG. 2 is a front view of the present invention.

FIG. 3 is a rear view of the present invention.

FIG. 4 is an overhead view of the present invention.

FIG. 5 is an underside view of the present invention; and, FIG. 6 is a perspective view of the present invention in use securing a wood anchor within a recessed area.

The broken lines showing the deep socket for a recessed anchor hold down in use is included for the purpose of illustration and forms no part of the claimed design.
